VINCENZO MARONNA, OF NEW YORK, N. Y.

COAT AND JACKET AND METHOD OF CONSTRUCTING THE SAME.

Application filed June 8, 1928. Serial No. 283,750.

This invention relates to the manufacture of coats, jackets and similar garments; and the object of the invention is to provide an improved method of attaching the several parts of a garment of this class in such manner as to permit of the machine stitching of all of the garment parts in coupling the same together to form the completely finished garment, eliminating the excessive labor costs involved in hand stitching as is the common practice in the manufacture of garments of this class, thus effecting a material saving in time as well as labor in the production of such garments in addition to producing stronger and more positive coupling of the separate parts thereof; and with these and other objects in view, the invention consists in a method of procedure for coupling garment parts in a simple, practical manner as more fully hereinafter described and claimed.

The invention is fully disclosed in the following specification, of which the accompanying drawing forms a part, in which the separate parts of my improvement are designated by suitable reference characters in each of the views, and in which:

Fig. 1 is a plan view showing the first steps in the method of coupling parts of a coat, jacket or the like together.

Fig. 2 is a sectional view showing a further step in the process.

Fig. 3 is a view similar to Fig. 2 showing a still further step of procedure.

Fig. 4 is a perspective detail view showing the next step in coupling the garment parts.

Fig. 5 is a perspective and sectional view showing the next step in the manufacture of the garment.

Fig. 6 is a perspective view of the sleeve and sleeve lining prior to the coupling thereof.

Figs. 7 and 8 show the methods of coupling the sleeve and lining.

Fig. 9 illustrates the sleeve coupled with the garment with the shoulder end of the lining free.

Fig. 10 is a perspective view illustrating the method of attaching the sleeve lining to the armhole of the garment; and,

Fig. 11 is a sectional detail view on the line 11-11 of Fig. 10, illustrating the attachment of the upper end of the sleeve lining to the garment.

In the manufacture of coats, jackets and like garments, it is a common practice to em-

ploy in the assemblage of the several parts of such garments considerable labor in the form of hand stitching or sewing, rendering such operations expensive, and further causing a considerable waste of time devoted to such hand labor. It is the principal object of my invention to provide a coat or jacket which is wholly constructed and assembled by machine stitching and to provide a method of producing a garment of this class.

The first operation in forming the coat consists in cutting out to the required sizes and styles, the several parts of the coat, such for example as the fronts, backs, facings, collar parts and sleeve parts, and including the several linings and paddings coupled with said parts.

In Fig. 1 of the drawing, I have shown at 12 and 13, the two parts of the back of a coat and in referring to a coat throughout the specification and claims, any similar garment is included. At 14 and 15, I have shown the two fronts of the coat, the two backs being stitched together at 16 and the free side of the back 12 stitched to the front 14 at 16^a, whereas the front 15 is secured to the part 13 of the back as shown at 16^b. All of said stitchings are machine stitchings, forming seams. In referring to stitching or stitchings throughout the specification, in all instances machine stitching is meant, as no hand stitching except in the use of bastings is employed.

Prior to stitching the fronts to the backs as above described, the usual forming or shaping V's designated by the lines 18 are formed therein. The usual canvas employed for reinforcing the fronts including the lapels, is basted in position prior to or after the fronts have been secured to the backs. These canvas pieces are indicated at 19, Fig. 2, and one is shown in full lines in Fig. 3, the basting thread being shown at 19^a.

The next step in the method consists in stitching one side edge of linings 20 for the two fronts 14 and 15 to the seams 16^a-16^b, one of which is seen at 20^a, Fig. 3, after which the side linings are folded upon the fronts. The next step consists in joining the shoulder portions of the fronts and back in the usual manner, forming the shoulder seams 21, one of which is seen in Fig. 4 of the drawing, after which the back 22 of the collar is stitched to the upper edge of the front and back of the coat as seen at 22^a, the front or facing 23 of the collar having been previous-

ly stitched to the collar back as at 23*, Fig. 5.

The inner facings 24 of the two fronts are now stitched to the free edges of the fronts as at 24* and turned inwardly upon said fronts, 5 also turning in and forming a piping finish 25 to the lower ends of the fronts and back in the usual manner, the facings 24 having piping edges as at 25*. The next step in the operation consists in basting the free edges of the 10 facings to the fronts to retain them in position, leaving a slight unbasted portion at the upper collar end of the facings to permit of the attachment of the collar thereto. The collar front is now stitched to the upper 15 edges of the facings as at 26 by turning or inverting the parts where the facings are unattached, in the usual manner.

The next step in the operation consists in stitching the upper edges of the front linings 20 to the side edges of the back strap lining 27, forming a seam as at 28. The upper edges of the front linings and the corresponding edges of the back strap lining are now stitched to the lower edge of the collar front 25 forming the seam 29. I now stitch the free side edges of the linings 20 to the free edges of the facings 24 as at 30, and also to the in-turned edges at the bottom of the fronts of the coat as seen at 30*, Fig. 5 of the drawing. 30 The latter stitching operations are accomplished by what is known as a blind stitching machine which produces a stitching that passes through the lining, facing and padding but does not pass through the fronts or 35 back of the coat, and is preferably arranged under the piping edges of the inturned portion. This stitching is also commonly known as a felling operation.

The coat proper, aside from the sleeves and 40 sleeve linings, is completed. In making the sleeves 31, first sew the outside seam 32 of the sleeve. Then, after making the usual sleeve lining 33, sew the lower edge of the lining to the sleeve as at 34 with the sleeve in 45 inverted position and arrange the buckram or other stiffening body 35 upon the lower end of the sleeve, note Figs. 7 and 8. Then sew the inside seam of both sleeve and sleeve lining in one line of stitching 36, note Fig. 8, 50 leaving in this operation an unstitched section or area on the inside seam of the sleeve lining 33, forming a pocket or opening 37. The sleeve is now reversed and passed over the lining in the usual manner, placing the 55 same in position to be attached to the sleeve holes of the coat. The sleeves proper 31 are now fitted and stitched to the jacket on the line of stitching or seam 38, note Fig. 9, but in this operation, the upper free edge of the 60 sleeve lining is not attached, as clearly seen in said figure.

To complete the formation of the coat, the upper edge of the sleeve lining must be stitched to the arm hole portion of the coat. 65 This is accomplished by first drawing both

sleeves into the interior of the coat through the arm holes, inverting the sleeves in this operation, after which the sleeves proper 31 are passed out through the openings 37 in the linings 33 to extend said linings around the 70 shoulder portions of the garment and beyond the arm holes therein to accessibly expose the arm hole portions of the garment as indicated at 39, Fig. 10 of the drawing, the free unattached edges of the sleeve linings 33 being 75 then fitted around the arm hole portions 39 and stitched in position as seen at 40, after which the sleeve linings are again passed downwardly over the sleeves or said sleeves passed inwardly into the linings through the 80 openings 37. Before moving the sleeves outwardly, the openings 37 are closed by a line of stitching, thus finishing the complete formation and mounting of the sleeves which may be now extended into proper position 85 outwardly with respect to the structure of the coat.

In Fig. 10 of the drawing, I have illustrated the position of the several parts, permitting of the stitching operation at 40, it being understood that the entire sleeve or at least the upper shoulder end of the sleeve has been turned through the opening 37 provided in the lining 33. Without this arrangement, this particular stitching operation could not 90 be accomplished on a sewing machine, nor in fact could the other assemblages of the coat be accomplished by machine stitching, without following substantially the specific method of procedure herein set out. 95

In forming the several stitchings or seams herein referred to, it will be understood that these seams are pressed in the usual manner, in order that the goods may assume the proper shape, and the several other commonly practiced steps in the manufacture of the coat are followed, such for example as the inclusion of paddings, interlinings and the like, but as this forms no specific part of my invention, they are not dealt with in any specific manner. 105

It will also be understood that my invention is not necessarily limited to the specific successive steps of the method herein described, and slight changes and modifications therein, may be made within the scope of the appended claims without departing from the spirit of my invention or sacrificing its advantages. 110

Having fully described my invention, what I claim as new and desire to secure by Letters Patent, is:

1. The herein described method of attaching sleeve linings to the arm hole portions of a garment by machine stitching which consists in arranging the attached sleeves on the 125 interior of the garment, providing one of the seams of the sleeve linings with an opening intermediate the end portions of said linings, passing the upper portions of the sleeves through said openings to expose the arm hole 130

portions of the garment and the upper unattached ends of the linings, to permit the stitching of said ends of the sleeve linings to the arm hole portions of the garment.

5 2. The herein described method of attaching a sleeve lining to the arm hole portion of a garment by machine stitching which consists in arranging the attached sleeve of such lining on the interior of the garment, providing one of the seams of the sleeve lining with an opening intermediate the end portions of said lining, passing the sleeve through said opening to expose the upper end portion of the sleeve and the arm hole of the garment, arranging the unattached end of the sleeve lining around the arm hole portion of the garment, and stitching the same thereto by the accessibility provided by the aforesaid exposure.

20 3. The herein described method of attaching a sleeve lining to the arm hole portion of a garment by machine stitching which consists in arranging the attached sleeve of such lining on the interior of the garment, providing one of the seams of the sleeve lining with an opening intermediate the end portions of said lining, passing the sleeve through said opening to expose the upper end portion of the sleeve and the arm hole of the garment, arranging the unattached end of the sleeve lining around the arm hole portion of the garment, stitching the same thereto by the accessibility provided by the aforesaid exposure, and then placing the sleeve 35 back into the sleeve lining and closing the opening in the sleeve lining by stitching.

4. The herein described method of attaching a sleeve and sleeve lining to the arm hole portion of a garment by machine stitching which consists in first attaching the shoulder portion of the sleeve to the arm hole portion of the garment, attaching the lower end of

the sleeve lining to the corresponding end of the sleeve and arranging the sleeve with the lining thereon on the inner portion of the garment, providing one of the seams of the lining with an opening arranged intermediate the attached and unattached ends thereof, then drawing the sleeve outwardly through said opening to expose the upper end portion of the sleeve and the arm hole portion of the garment, and arranging the upper unattached end of the sleeve lining over the shoulder and body portion of the garment around the arm hole, and then alining and stitching 55 the free edge of the lining to the arm hole portion of the garment.

5. The herein described method of attaching a sleeve and sleeve lining to the arm hole portion of a garment by machine stitching, which consists in first attaching the shoulder portion of the sleeve to the arm hole portion of the garment, attaching the lower end of the sleeve lining to the corresponding end of the sleeve and arranging the sleeve with the lining thereon on the inner portion of the garment, providing one of the seams of the lining with an opening arranged intermediate the attached and unattached ends thereof, then drawing the sleeve outwardly through said opening to expose the upper end portion of the sleeve and the arm hole portion of the garment and arranging the upper unattached end of the sleeve lining over the shoulder and body portion of the garment around the arm hole, then alining and stitching the free edge of the lining to the arm hole portion of the garment, and then reversing the parts and closing the opening in the sleeve lining.

In testimony that I claim the foregoing as my invention I have signed my name this 4th day of June, 1928.

VINCENZO MARONNA.
